UNITED STATES PATENT OFFICE

166,043

LAPSED TIME TELEPHONE ATTACHMENT

Gordon B. Miller, Glendale, Ohio, assignor to
Gordon B. Miller & Co., Cincinnati, Ohio, a
corporation of Ohio

Application November 18, 1949, Serial No. 6,135

Term of patent 14 years

(Cl. D26—14)

To all whom it may concern:

Be it known that I, Gordon B. Miller, a citizen of the United States of America, residing at Glendale, in the county of Hamilton and State of Ohio, have invented a new, original, and ornamental Design for a Lapsed Time Telephone Attachment, of which the following is a specification, reference being had to the accompanying drawing, forming a part hereof.

Referring to the figures:

Figure 1 is a top plan view of a lapsed time telephone attachment, showing my new design;

Figure 2 is a front elevational view;

Figure 3 is a side elevational view thereof taken from the left of Figure 2; and

Figure 4 is a perspective view illustrating the device attached to a telephone.

The dotted line disclosure appearing in Figure 4 of the drawing is for illustrative purposes only.

I claim:

The ornamental design for a lapsed time telephone attachment, substantially as shown and described.

GORDON B. MILLER.
